CLAIM

The ornamental design for a pry guard header element, as shown and described.

DESCRIPTION

FIG. 1 is a fragmentary top perspective view of the pry guard header element showing my design;

FIG. 2 is a top plan view thereof broken away to indicate indeterminate length;

FIG. 3 is a bottom plan view thereof broken away to indicate indeterminate length;

FIG. 4 is a front elevation view thereof in which the rear elevational view is a mirror image of the front view;

FIG. 5 is a right elevational view thereof broken away to indicate indeterminate length; and,

FIG. 6 is a left elevational view thereof broken away to indicate indeterminate length.
